UNITED STATES PATENT OFFICE.

ALFRED WILLIAM BENNIS, OF BOLTON, ENGLAND.

WATER-HEATING AND STEAM-GENERATING BOILER.

Application filed August 3, 1925. Serial No. 47,929.

The present invention relates to improvements in water heating systems and more particularly to water tube steam generators.

The invention is described with particular reference to water heating or steam generating boilers in which inclined water tubes are connected in banks to headers, water legs or to drums at the front and rear of such banks, all in appropriate combination with main steam, water and mud drums, and other connections.

One object of the present invention is to provide a more efficient arrangement of the heating surface of the inclined tubes by which a portion of the heating surface of the tubes is removed from the rearward or exit portion of the boiler and placed in the forward or first pass portion of the boiler where such heating surfaces will be subject to the more intense heat of the furnace.

It is further desired to employ vertical or semi-vertical, circulating tubes passing between the tubes of the upper portion of the boiler in a location suitable for the support of a baffle wall situated between the first and second pass of the boiler.

According to the present invention the main boiler tubes are divided into two or more separate banks, the upper bank being materially longer than the bank immediately below it.

The invention is more particularly described with reference to the accompanying drawings, in which:

Figure 1 is a view in elevation of one form of construction and arrangement of the tubes of the boiler according to the present invention, the tubes being inclined in one direction, namely upwardly from front to rear of the boiler.

Figure 2 is a view in modification of Figure 1, in which the upper bank of tubes is inclined in an opposite or different direction to the lower bank of shorter tubes.

In water tube boilers it has generally been the practice to arrange the main water tubes in groups or banks which are of similar length. By the invention the banks of tubes are of differing length. As may be seen from Figure 1, products of combustion from a chain grate or other furnace 1 passes up through a bank of short tubes 2 inclined upwardly and then through the first pass of a second bank of tubes 3 whence they are deflected to pass down on the opposite side of the partition wall 4 through the second pass

of the bank of tubes 3 before proceeding to the exit flue 5. A superheater unit 6 may be placed in the space between the banks of tubes 2 and 3. In the arrangement shown 60 the headers 7, 8 of the short bank of tubes 2 connects direct by pipes 9, 10 respectively, to the front drum 11 and intermediate drum 12, whilst the bank of tubes 3 has its own pipe connections 13, 14 to the front and rear 65 drums 11, 15. The drum 11 is, therefore, common to both banks of tubes. Connections 16, 17 are provided between the drums 11, 12 and 15.

Figure 2 shows an arrangement by way of example where the lower short bank of tubes 22 lies at a different inclination, namely, upwardly to the inclination of the long bank of tubes 23, which are inclined downwardly. Upcomers 51 from the lower bank of tubes 75 22 are used to help in forming baffles or to act as a support for said baffles in the upper bank of tubes.

It will be obvious that many further variations are possible in the arrangement of the 80 particular details of the structure within the scope of the appended claims.

I declare that what I claim is:—

1. A water heating and steam generating boiler comprising in combination a furnace grate, a short bank of boiler tubes and headers at each end thereof, through which the furnace gases pass directly upwards, a materially longer bank of tubes and headers at each end thereof and three drums above 80 said banks of tubes, one drum being common to one end of both the short and long bank of tubes whilst the two others are each separately connected to the headers at the opposite ends of the banks of tubes. 95

2. A water heating and steam generating boiler comprising in combination a furnace grate, a short bank of boiler tubes and headers at each end thereof, through which the furnace gases pass directly upwards, a materially longer bank of tubes and headers at each end thereof oppositely inclined to the short bank of tubes, and three drums above 100 said banks of tubes, one drum being common to one end of both the short and long bank of tubes, whilst the two others are each separately connected to the headers at the opposite ends of the banks of tubes.

3. A water heating and steam generating boiler comprising in combination a furnace 110 grate, a short bank of boiler tubes and headers at each end thereof, through which the

furnace gases pass directly upwards, a materially longer bank of tubes and headers at each end thereof, a partition wall dividing the length of the longer bank of tubes and lying substantially in the plane of an end header of the short bank of tubes, and three drums above said banks of tubes, one drum being common to one end of both the short and long bank of tubes whilst the two others are each separately connected to the headers at the opposite ends of the banks of tubes.

4. A water heating and steam generating boiler comprising in combination a furnace grate, three upper drums horizontally disposed with regard to one another, pipe con-

nnections between said drums, a short bank of tubes through which all the furnace gases pass directly upward, a materially longer bank of tubes, connection pipes to connect said tubes of the shorter bank to one end drum and the central drum, connection pipes to connect said tubes of the longer bank to both end drums, and a partition wall dividing the length of the longer bank of tubes, said wall being supported by the connection pipes from said central drum to the shorter bank of tubes.

In witness whereof, I have hereunto signed my name this 22nd day of July, 1925.

ALFRED WILLIAM BENNIS.
